UNITED STATES PATENT OFFICE.

GUSTAV DE GRAHL, OF ZEHLENDORF, NEAR BERLIN, GERMANY.

APPARATUS FOR AUTOMATICALLY REGULATING THE DRAFT IN BOILER-FURNACES.

1,079,853.

Specification of Letters Patent. Patented Nov. 25, 1913.

Application filed January 6, 1912. Serial No. 669,828.

To all whom it may concern:

Be it known that I, GUSTAV DE GRAHL, a subject of the German Emperor, and residing at Zehlendorf, near Berlin, Germany, 5 have invented certain new and useful Improvements in Apparatus for Automatically Regulating the Draft in Boiler-Furnaces, of which the following is a specification.

The subject-matter of my invention is a 10 device for the fire-doors of boiler-furnaces for regulating the admission of auxiliary air into the fire-box.

My device substantially consists in the fire-door being provided with two superposed air-conduits for automatically admitting air into the fire-box. In these conduits I arrange flaps or valves whose maximum stroke can be adjusted independently of one another, so that air can be admitted at various elevations from without into the fire-box and the maximum quantity of the same can be regulated according to the adjustment of the stroke.

One illustrative embodiment of my invention is represented by way of example in the accompanying drawings, wherein:

Figure 1 is a front elevation of a fire-door provided with my device. Fig. 2 is a vertical section through the same, and Figs. 3 20 and 4 show parts of the fire-door on an enlarged scale, Fig. 3 being a side elevation, partly in section, and Fig. 4 a cross-section on line A—B in Fig. 3.

Referring to the drawings, 1 designates 35 the wall of the fire-box having the aperture 3 bounded by the ring 2 for the insertion of fuel. The plate 4 carrying the journal 5 for the vertical door-shaft 6 is mounted on the outer wall of the fire-box. The two 40 strap-hinges 7, 8 are fast on the shaft 6 whose rotation is imparted to the door owing to the shoulder 10 of the sleeve 9 fast on the shaft coacting with a corresponding recess in the hinge 7. The rod 11 terminates 45 at one end in the handle 12 and its other end is pivotally connected by the pivot 13 to the forked head 14 of the shaft.

In the closed position of the door shown 50 in Fig. 1 the rod 11 rests behind the latch 16. The door is provided with air-conduits, two of which 17, 18 and 17', 18' are arranged in pairs one over another. A valve 19 is mounted to rock about a pivot 43 in each of the lower conduits 17, 17', and a 55 valve 20 is mounted to rock about a pivot

44 in each of the upper conduits 18, 18'. The lower conduits are provided with heating ribs 21 and 21', and the upper conduits with similar ribs 22 and 22'. Further, on one side wall of each pair of conduits is fixed a segment 45 connected by arms 46 with a sleeve 47. Each of the latter extends above the adjacent appertaining valve through the lateral wall of the conduits, and carries a revoluble pivot 48 which carries on its end 60 projecting into the air-conduit an arm 49 acting as a stop for the valve, and on the other end a lever 50. Each lever carries a handle 51 having a recess 52 (Fig. 4). The spring 53 in each recess 52 acts against the 65 head 54 of the pointed pin 55 which is displaceably mounted in the handle 51 and provided with a nut 56.

Each of the segments 45 has a series of 70 notches or holes 57 in which the pointed ends 75 of the heads 54 can rest. The arms 49 are provided with springs 58 serving as resilient stops for the valves 19 and 20. The position of the arms 49 relatively to the valves 19, 20 is such that as soon as the heads 54 engage in the lowest holes 57, the arms 49 constituting the stops for the valves allow the valves to open a minimum amount just sufficient for cooling the door.

The shafts 23, 24 are journaled in the fire-door below the valves 19 and 20. The lever 25 is fast on the shaft 23 and the lever 26 is fast on the shaft 24, and these two levers are connected together by a jointed rod in such manner that the motion of the shaft 23 is imparted to the shaft 24 and reversely. This jointed rod comprises the two parts 60, 61 of which the part 60 is pivotally connected with the lever 25 and the part 61 with the lever 26. The two parts 60, 61 are 80 screw-threaded at their ends 62, 63 and screwed into the sleeve or nut 64. By rotating the nut 64 the rod 60, 61 can be 85 lengthened or shortened as desired.

The levers 28, 28' are fast on the shaft 23 95 and the levers 29, 29' on the shaft 24. The lever 30 is fast on the shaft 23. The latter lever runs out into a pivot 31 carrying the anti-friction roller 32. The cataract-cylinder 35 is arranged under the shaft 6 with 100 the axes in alinement. The piston 34 fast on the piston rod 33 is movable in the cataract-cylinder. The piston-rod passing through the stuffing-box 41 carries at its upper end the plate 42 which, when the piston 110

rises, acts against the roller 32. The pipe 36 opens above into the cylinder 35 which is connected below with the atmosphere.

37 designates a steam pipe provided with 5 the valve 38. Between the pipes 36 and 37 is connected an injector comprising the casting 40 and the nozzle 39.

The described apparatus operates as follows: As soon as a pressure below atmos-

10 pheric occurs in the fire-box when the fire-door is shut, the valves 19, 20 are automatically opened and admit air into the combustion chamber. By adjusting the levers 49, 50 the maximum amount which the valves can open can be regulated in each air con-

15 duct. For example, if air is principally to enter into the fire-box through the lower air conduit 17, 17' the stops 49 for the valves will be adjusted so that the lower valves 19 have a materially larger maximum stroke 20 than the upper valves 20. The valves 19, 20 may be opened positively by causing the piston 34 in the cataract to be elevated by 25 suction by means of the injector 39, 40. The motion of the piston is then imparted to the lever 30 and to the shaft 23 and through the medium of the jointed rod 60, 61 to the shaft 24. The shafts 23, 24 then act through their 30 levers 28 and 29, respectively, on the valves 19, 20, respectively, and lift the same. The arrangement may be such that this piston 34 is automatically lifted by suction as soon as the main blast is shut down and the auxiliary blast operated, to which end the steam pipe 37 will be connected with the pipe leading 35 to the auxiliary blast.

If it is wished to transmit the motion of the cataract-piston only to the upper or only to the lower valves, the jointed rod 60, 61 will be correspondingly altered in length by 40 moving the nut 64. If the jointed rod be shortened by screwing the nut 64 clockwise (Fig. 3) when the piston 34 is lifted the valves 19 will open sooner than the 45 valves 20, whereas, reversely, *i. e.* when the rod is lengthened by turning the nut 64 counter-clockwise, the valves 20 will be opened earlier than the valves 19.

I claim:—

50 1. In apparatus for automatically regulating the draft in furnaces of locomotive-boilers the combination of a fire-box and a horizontally opening fire-door provided with air-conduits, arranged in pairs one over another opening below into the atmosphere and above into the fire-box, and means for admitting air in turns to different levels of the fire-box said means being controlled by the vacuum in the fire-box.

60 2. In apparatus for automatically regulating the draft in furnaces of locomotive-boilers the combination of a fire-box and a horizontally opening fire-door provided with air-conduits arranged in pairs one over the 65 other opening below into the atmosphere

and above into the fire-box, non-return flap-valves in said conduits, said valves being pivoted at one end and adapted to open automatically under the influence of the vacuum in the fire-box and stops positively connected with said valves for limiting the strokes of said valves, each of said stops being individually adjustable independent of each other.

3. In apparatus for automatically regulating the draft in furnaces of locomotive-boilers the combination of a fire-box and a horizontally opening fire-door provided with air-conduits, arranged in pairs one over another opening below into the atmosphere 70 and above into the fire-box, non-return flap-valves in said conduits, said valves being pivoted at one end and adapted to open automatically under the influence of the draft in the fire-box; the individual flap-valves of 75 each pair of conduits possessing different inclination toward the horizontal in their closed positions.

4. In apparatus for automatically regulating the draft in furnaces of locomotive-boilers the combination of a fire-box and a horizontally opening fire-door provided with air-conduits, arranged in pairs one over another opening below into the atmosphere 80 and above into the fire-box non-return flap-valves in said conduits, said valves being pivoted at one end and adapted to open automatically under the influence of the draft in the fire-box; the individual flap-valves of 85 each pair of conduits possessing different inclination toward the horizontal in their closed positions.

90

5. In apparatus for automatically regulating the draft in furnaces of locomotive-boilers the combination of a fire-box and a horizontally opening fire-door provided with air-conduits, arranged in pairs one over another, opening below into the atmosphere and above into the fire-box, non-return flap-valves in said conduits, said valves being 95 pivoted at one end and adapted to open automatically under the influence of the draft in the fire-box, the individual flap-valves of 100 each pair of conduits possessing different inclination and the lower one of said pair horizontal in closed position.

5. In apparatus for automatically regulating the draft in furnaces of locomotive-boilers, the combination of a fire-box and a horizontally opening fire-door provided with air-conduits, arranged in pairs one over another, opening below into the atmosphere and above into the fire-box, non-return flap-valves in said conduits, said valves being 105 pivoted at one end and adapted to open automatically under the influence of the draft in the fire-box, the individual flap-valves of 110 each pair of conduits possessing different inclination toward the horizontal in their closed position and adjustable stops positively connected with said valves for limiting the strokes of said flap-valves.

6. In apparatus for automatically regulating the draft in the furnaces of steam 115 boilers, the combination of a fire-box, and a horizontally-opening fire-door provided with internally-ribbed air-conduits, arranged in pairs one over another, opening below into the atmosphere and above into the fire-box, 120 and a non-return valve capable of opening automatically under the influence of the draft in the fire-box mounted in each air-conduit; a shaft under the lower valves, a second shaft under the upper valves, means 125 130

for imparting the movement of one shaft to the other, a cataract containing a piston, means for imparting the motion of said piston to one of said shafts, and arms fast on each of said shafts for opening the valves when the said shafts are rotated.

7. In apparatus for automatically regulating the draft in the furnaces of steam boilers, the combination of a fire-box, and a horizontally-opening fire-door provided with internally-ribbed air-conduits, arranged in pairs one over another, opening below into the atmosphere and above into the fire-box, and a non-return valve capable of opening automatically under the influence of the draft in the fire-box mounted in each air-conduit; a shaft below the lower valves, a second shaft below the upper valves, a lever-arm secured on each of the said shafts, a rod of variable length pivotally connected to the lever-arms, a cataract containing a piston, means for imparting the motion of said piston to one of the two shafts, and arms fast on said shafts for opening said valves when the said piston is lifted.

8. In apparatus for automatically regulating the draft in the furnaces of steam boilers, the combination of a fire-box, and a horizontally-opening fire-door provided with internally-ribbed air-conduits, arranged in pairs one over another, opening below into the atmosphere and above into the fire-box, and a non-return valve capable of opening automatically under the influence of the draft in the fire-box mounted in each air-conduit; a shaft below the lower valves, a second shaft below the upper valves, a lever-arm secured on each of the said shafts, a rod of variable length pivotally connected to the lever-arms, a cataract containing a piston, means for imparting the motion of said piston to one of the two shafts, and arms fast on said shafts for opening said valves when the said piston is lifted.

In testimony whereof, I affix my signature in the presence of two witnesses.

GUSTAV DE GRAHL.
